FLUID PRESSURE MOTOR

Filed Dec. 17, 1923

Fig. 5.

Ernest G. Garton Inventor: ## UNITED STATES PATENT OFFICE

ELMER G. GARTIN, OF CLAREMONT, NEW HAMPSHIRE, ASSIGNOR TO SULLIVAN MACHINERY COMPANY, A CORPORATION OF MASSACHUSETTS

FLUID-PRESSURE MOTOR

Application filed December 17, 1923. Serial No. 681,146.

My invention relates to fluid pressure motors.

An object of my invention is to provide an improved pressure fluid motor. Another object of my invention is to provide an improved percussive motor having an improved valve mechanism. Still another object of my invention is to provide an improved pressure fluid percussive motor especially adapted for rock drilling purposes provided with an improved valve mechanism of the multiple spool type having an improved guiding means, lubricating means, and buffer venting means therefor, and arrangement of parts thereof. These and other objects and advantages of my invention will, however, hereinafter more fully appear.

In the accompanying drawings I have shown for purposes of illustration one form 20 which my invention may assume in practice.

In these drawings,—

Fig. 1 is a central longitudinal vertical sectional view of a drilling motor in which an illustrative form of my invention is incorporated, the view being partially in side elevation.

Fig. 2 is a view similar to that shown in Fig. 1 with parts assumed in different positions.

Figs. 3 and 4 are detail end elevation views 30 of a portion of my improved mechanism.

Fig. 5 is a perspective view illustrating the locking member.

In this illustrative form of my invention, I 35 have shown a pressure fluid percussive motor of the valved type generally designated 1, which comprises a cylinder 2 having a bore 3 in which a piston 4 is reciprocable. The piston 4 is provided with a projecting striking bar 5 adapted to percussively actuate a drill steel (not shown) suitably carried by the front end of the drilling motor in a well known manner. The opposite ends of the bore of the cylinder 2 are closed by head members 6 and 7 suitably held in the desired assembled relation by means of side rods (not shown) in the usual manner.

Pressure fluid is distributed alternately to the ends of the cylinder by means of passages 50 8 and 9, the supply and exhaust of pressure

fluid through the distribution passages 8, 9 being controlled by a valve mechanism of improved construction, generally designated 10. This valve mechanism comprises a casing or chest 11 in which suitable valve bushings 12 are so arranged as to form a chamber having end portions 13 of slightly smaller diameter than its central portion 14. Herein, the passages 8, 9 communicate with the valve chamber adjacent the ends of the enlarged central bore 14, terminating in annular grooves 15 and 16. Adjacent the extremities of the smaller bores 13, ports 17 and 18 connect throwing or reverse passages 19 and 20 with the valve chamber, these passages at their opposite ends communicating with the bore of the cylinder 2 by longitudinally spaced ports 21 and 22. Intermediate the port 17 and groove 15 and port 18 and groove 16, respectively, in the valve chest there are formed annular grooves 23 and 24, which grooves communicate by ports 25 and 26 with an exhaust passage 27 formed in a boxlike member 28 suitably secured to the top of the valve chest. As illustrated, a valve, generally designated 29, is arranged within the valve chest and is herein of the three spool type and comprises recessed end spools or heads 30 fitting the bores 13 and a central spool portion 31 of slightly larger diameter fitting the bore 14, the heads 30, 31 being connected by reduced portions 32. Herein, it will be observed that the outer ends of the bores 13 are closed by buffer members or plugs 33 and 34, with which the recessed ends of the valve are adapted to engage, which are held in the desired rigid assembled relation by means of flattened surfaces 33' and 34' engaging a corresponding flattened surface on the cylinder 2 and a centrally disposed longitudinally extending bolt 35 provided with a head 36. The head 36 is provided with flattened portions 37 which are adapted to engage the sides of a slot or groove 38 in the valve buffer 33 thereby holding the buffers and bolt in rigid non-rotating relation. This bolt 35 is provided with a nut 39 which is held in the desired tightened position by means of a locking member 40 engaging the sides of a slot or groove 41 in the buffer plug 34. Herein, it will be

noted that the valve bushings and valve buffers are held in the desired assembled relation by this bolt, the nut being tightened and positively locked in position, an upturned lip portion 42 on the locking member engaging a flattened surface on the nut thereby preventing the loosening of the same and the derangement of the parts. As illustrated, the valve 29 is provided with a central longitudinal 10 extending bore 43 through which the bolt 35 extends and the walls of this bore cooperate with this bolt in guiding the valve. Herein, it will be observed that the bolt 35 is traversed by a plurality of radially extending 15 longitudinally spaced ports 45 which communicate with the valve chamber at points adjacent the inner ends of the buffer plugs and which communicate by way of passages 46 extending coaxially through the bolt to exhaust. Formed intermediate the passages 45 in the bolt is a spiral groove 47 to which lubricant is supplied through apertures 48 and 49 in the reduced portions 32 of the valve intermediate the spools. Lubricant passes from 20 any suitable source of supply, herein from the motor lubricating mechanism (not shown), through the apertures 48, 49 to the spiral groove thereby reducing the friction of the valve sliding on the bolt. Herein, a fluid supply port communicates with an annular space 50 formed between the ends of the bushings 12 in the central part of the valve chest.

In the operation of my improved mechanism, it will be noted that when the valve assumes the position shown in Fig. 1, pressure fluid passes from the inlet space 50 to the left of the central spool 31 of the valve and by way of passage 8 to the rear end of the 30 piston 4 to cause a forward movement thereof. Simultaneously the front end of the cylinder is connected by passage 9 to exhaust. This piston 4 will accordingly move forward and during its forward movement uncovers 35 the port 22 communicating with the reverse passage 20, admitting pressure fluid to the right hand end of the valve, reversing the same and causing it to assume the position in Fig. 2. The operation of the motor is then 40 reversed causing the piston to move rearward, the passage 9 communicating with the fluid inlet and the passage 8 leading to the exhaust. Herein, it will be noted that the spaces 45 in the valve chamber between the outer ends of the valve and the inner ends of the buffer plugs 33, 34 are alternately opened to exhaust under the control of the valve by means of the port 45 and passage 46 formed in the bolt 50 35, leading to the atmosphere which prevents a pressure from building up and thereby facilitates the throwing movements of the valve. Furthermore, it will be noted that the valve is guided and lubricated by means 60 of the bolt 35 and the spiral groove respec-

tively thereby reducing friction to a minimum between the operating parts.

As a result of my improvement it will be noted that a valve mechanism of compact, rugged character is produced having vented buffers and improved lubricating and guiding mechanism while the valve parts are held in the desired assembled relation in a simple manner and rigidly locked. It will further be noted that this improved valve mechanism may be applied to a drill of standard construction with a minimum of change, the only necessary changes being the slotted valve buffers having enlarged central bores extending therethrough, a valve having a central bore, a bolt extending through the bores in the buffers and the valve, and means for locking the parts in assembled relation. These and other objects and advantages of my improved construction will be clearly apparent to those skilled in the art.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a pressure fluid motor, a cylinder, a piston reciprocable therein, and means for effecting reciprocation of said piston including a valve chest, a valve therein, buffers limiting movement of said valve, a center bolt extending through said valve for retaining said buffers in assembled relation, and means disposed within said center bolt for alternately venting the space between said buffers and the ends of said valve to exhaust the pressure on the total area of the ends of said valve.

2. In a pressure fluid motor, a cylinder, a piston reciprocable therein, and means for effecting reciprocation of said piston including a valve chest, a valve therein having throwing areas at opposite ends thereof, buffers limiting movement of said valve, and a ported center bolt for slidably receiving said valve and for retaining said buffers in assembled relation, said ported center bolt being adapted to alternately vent the space between said buffers and the ends of said valve to exhaust the pressure acting on said throwing areas.

3. In a pressure fluid motor, a cylinder, a piston reciprocable therein, and means for effecting reciprocation of said piston including a valve chest, a valve therein, buffers limiting the movement of said valve, and means for retaining said buffers in assembled relation including a center bolt extending through said valve, locking means therefor, and means controlled by said valve for

lubricating said bolt including a spiral groove and ports in said valve communicable therewith.

4. In a pressure fluid motor, a cylinder, a piston reciprocable therein, means for effecting reciprocation of said piston including a valve chest, a valve therein having throwing areas on opposite ends thereof, buffers limiting movement of said valve, a center bolt extending through said valve for retaining said buffers in assembled relation, and means provided by said center bolt and controlled by said valve for alternately venting said throwing areas on the ends of said valve.
5. In a pressure fluid motor, a cylinder, a piston reciprocable therein, means for effecting reciprocation of said piston including a valve chest, a valve therein, buffers limiting movement of said valve, a center bolt extending axially through said valve for retaining said buffers in assembled relation, and means provided by said center bolt comprising separate passages alternately opened and closed by said valve for venting the space between the ends of said buffers and the ends of said valve to exhaust the total end areas on said valve.
6. In a pressure fluid motor, a cylinder, a piston reciprocable therein, means for effecting reciprocation of said piston including a valve chest having a bore, a valve therein having recessed end portions, buffer plugs having portions projecting within the bore in said valve chest and with which the recessed portions of said valve alternately engage, a center bolt extending through said valve for retaining said buffer plugs in assembled relation, and means provided by said bolt and controlled by said valve for alternately venting the space between the projecting portions of said buffer plugs and the recessed portions of said valve and the space around said projecting portions.
7. In a pressure fluid motor, a cylinder, a piston reciprocable therein, and means for effecting reciprocation of said piston including a valve chest, a valve therein, buffers limiting movement of said valve, means for retaining said buffers in assembled relation including a center bolt on which said valve slides, locking means therefor, means provided by said center bolt for alternately venting the space between the ends of said buffers and the ends of said valve, and means provided by said bolt intermediate said vent means for lubricating the valve.

In testimony whereof I affix my signature.
ELMER G. GARTIN.
